UNITED STATES PATENT OFFICE.

JOHN C. DAGGETT, OF BOSTON, ASSIGNOR OF ONE-HALF TO CHARLES H. COLBURN, OF MILFORD, MASSACHUSETTS.

SEWING-MACHINE FEED.

SPECIFICATION forming part of Letters Patent No. 373,391, dated November 15, 1887.

Application filed February 8, 1887. Serial No. 226,930. (No model.)

To all whom it may concern:

Be it known that I, JOHN C. DAGGETT, of Boston, county of Suffolk, and State of Massachusetts, have invented an Improvement in Sewing-Machine Feed-Regulators, of which the following description, in connection with the accompanying drawings, is a specification, like letters on the drawings representing like parts.

- 10 This invention has for its object to improve the construction of wax-thread sewing-machines whereby the length of the feed may be changed quickly and without stopping the machine.
- 15 My invention is especially applicable to what is known as the "Campbell" machine, it being represented, substantially, in United States Patent No. 253,156, dated January 31, 1882.
- 20 The machine represented in the said patent has a graduated scale-bar provided with a series of holes, which are engaged by a pin forming part of a thumb-latch connected with the lever, which regulates the position of a block that determines the extent of motion imparted to the feed slide, and hence the length of the feed. By the employment of a graduated scale-bar having a series of holes it has been found most difficult to gain for the feed 25 the desired length of stroke, for the holes determine the minimum adjustment which it is possible that the lever may have. To overcome this difficulty and enable the throw of the lever to be adjusted with greater accuracy, 30 I have provided two adjustable stops, controlled as to their position by a screw or otherwise, the said stops determining the two positions to be occupied by the feed-regulating lever when the maximum and minimum length 35 of stitches are to be made.
- 40 Figure 1 is a front elevation of a sufficient portion of a wax-thread sewing-machine substantially such as represented in the said patent to enable my invention to be understood.

45 Fig. 2 is a right-hand end elevation of Fig. 1. Fig. 3 is a top or plan view of Fig. 1, and Figs. 4 and 5 are details showing the rock-shaft and means co-operating with it and the feed-graduating lever and feed-slide to regulate the 50 length of stroke of the feed-slide.

The feed-slide G, the stationary head-plate g, the feed-graduating lever g', having its fulcrum at g'', the link f³, the coupled block f⁴, extended through an inclined slot in the feed-slide, and the block f⁵, entering a groove or a slot, f⁶, in the arm f² of the rock-shaft f', and the awl-carrying bar F are all common to United States Patent No. 253,156, where like devices are designated by like letters, and wherein their operation is fully described. 55 Herein I have attached to the head of the machine two ears or projections a a', in which I have placed a guide-bar, b, the latter being held in position by means of set-screws b'. This guide-bar serves the purpose of a support 60 for two stops, c c', each adjustably attached by set screws, as c² c³, the portions c⁴ of the said stops projecting horizontally across the path of movement of the feed-graduating lever g', so that the said lever will be arrested both in 65 its elevated and depressed positions by one or the other of the said stops c c', the position of the stop c determining the short stitch and that of the stop c' the long stitch to be made. The higher the stop c the shorter the stitch, and 70 the lower the stop c' the longer the stitch, the long or short stitch being made according to which stop arrests the lever g'. By employing the stops c c' the stitches may be adjusted very 75 finely, so as to more exactly and accurately 80 space or divide up the stitches to be made in a boot or shoe than is possible where a hole has to be entered by a pin, for the number of adjustments which may be made of the stops is much in excess of the number of holes that 85 can be made in a bar for the reception of a pin of suitable strength to arrest and hold the feed-graduating lever in a definite position.

I have herein shown the feed-graduating lever g' as provided with a latch, g¹, which is 90 extended over and bears upon the sector n, the latch producing sufficient friction upon the sector to prevent the lever from jumping or from moving out of position, except when moved by the operator taking hold of the same. 95 I do not, however, desire to limit my invention to the employment of this latch, nor do I desire to limit my invention to the particular shape of the rod or guide b upon which the stops are adjustably mounted, for the said 100

stops may be made adjustable upon a suitable guide of any well-known construction.

I claim—

1. The combination, with the machine-head 5 and the feed-graduating lever, of the stationary rod *b*, attached to the front of the said head, the adjustable stops *c* and *c'*, having portions extending horizontally across the path of movement of the said lever, and the set-screws 10 for securing the said stops in place, substantially as set forth.

2. The combination, with the machine-head having ears or projections *a* and *a'* at the front thereof, of the feed-graduating lever, the rod

b, attached to the said ears or projections, the 15 stops *c* and *c'*, having portions extending horizontally across the path of the said lever, the set-screws for securing said stops in place, the sector or bar *n*, and the friction-lever *g'* and its spring, substantially as set forth.

In testimony whereof I have signed my name 20 to this specification in the presence of two subscribing witnesses:

JOHN C. DAGGETT.
